UNITED STATES PATENT OFFICE.

EUGENE L. CAVANNA, OF CHICAGO, ILLINOIS.

SHOE SUPPORT AND FORM.

Application filed October 9, 1924. Serial No. 742,531.

To all whom it may concern:

Be it known that I, EUGENE L. CAVANNA, a citizen of the United States, residing at Chicago, in the county of Cook and State of Illinois, have invented certain new and useful Improvements in Shoe Supports and Forms, of which the following is a specification.

This invention relates to improvements in 10 shoe supports and forms, and has for its object to provide a device whereby one shoe or a pair thereof may be firmly supported in position in such wise that the shoe will also be held in its normal shape and with 15 the upper facing out to present a more pleasing appearance.

This and other objects will be more fully set forth and described in the following specification and shown in the accompanying drawing, in which—

Fig. 1 is a side elevation showing an embodiment of my invention, a lady's slipper being illustrated in dotted lines as supported thereby, a portion of the toe form being 25 broken away for clearness.

Fig. 2 is a front elevation of the same embodiment.

Fig. 3 is a detail.

In the drawing, 10 indicates generally a 30 supporting device formed of spring wire with the spaced toe portions 10^a, to each of which is secured a toe form or shield 10^b. The outer part of each toe portion 10^a is connected by the bridging portion 10^c as shown in Fig. 2. The inner portions are extended, offset and coiled as indicated at 10^d, this giving additional spring or resilience for the toe portions. Downwardly from the coiled portions 10^d extend the supporting portions 10^e, which are angularly 40 bent and secured beneath the clamp 12 to a transverse bar 13, which is provided with the inturned edge or flange 13^a engageable by the outer heel of a supported shoe. This 45 bar 13 may be secured in any suitable manner to a wall, door, board or the like.

Projecting rearwardly from and secured to each of the toe forms 10^b is a strip of spring metal 15 having the angularly bent 50 heel engaging portion 15^a and the coiled finger engaging portion 15^b.

In use of my device the shoe or slipper to be supported is moved to insert the toe engaging portion or form 10^b into the toe of 55 such shoe, after which the member is moved

rearwardly to permit moving of the heel over the flange 13^a, as illustrated in Fig. 1. This places the shoe under tension due to the tension of the wire and its coiled arrangement. To prevent distortion of the 60 supported shoe from normal shape, the member 15 is forced into the shoe to contact with the inner heel portion, as illustrated in Fig. 1, this member 15 being of sufficient 65 length to insure its bending when so positioned, thereby setting up a tension which will counteract the distorting tension imparted by the shoe support. To remove the member 15 from engaging position the finger portion 15 may be readily engaged 70 and pulled out by the user.

It will be obvious that my invention is susceptible of modification, and I do not wish to be restricted to the form shown, except as defined in the appended claims. 75

What I claim is:

1. In combination, a shoe support formed of wire, comprising spaced toe engaging portions, and a transverse supporting strip attachable to a wall or the like, said shoe 80 support comprising portions attached to said supporting strip, said toe engaging portions being extended toward said supporting portions and the wire coiled at the juncture therewith, said strip being provided with 85 means to engage the heels of supported shoes or the like, said toe engaging portions and said heel engaging means being so constructed and arranged as to support shoes 90 under yielding tension.

2. In combination, a shoe support formed of wire, comprising spaced toe engaging portions, a transverse supporting member, said shoe support comprising portions attached to said supporting member, said toe 95 engaging portions being extended toward said supporting portions and the wire coiled at the juncture therewith, and means extending rearwardly from said toe engaging portions and insertible in a supported shoe or 100 slipper to maintain the same in normal shape, said last named means adapted to engage the extreme interior portion of the heel of said shoe.

3. In combination, a shoe support formed of wire, comprising spaced toe engaging portions, a transverse supporting member, said shoe support comprising portions attached to said supporting member, said toe 105 engaging portions being extended toward 110

said supporting portions and the wire coiled at the juncture therewith, and means extending rearwardly from said toe engaging portions and insertible in a supported shoe or slipper to maintain the same in normal shape, said last named means adapted to engage the interior portion of the heel of said shoe and being formed of spring metal and of such length as to require bending for insertion in the supported shoe or the like.

4. In combination, a shoe support formed of wire comprising spaced toe engaging portions, a transverse supporting member, said

shoe support comprising portions attached to said supporting member, said toe engaging portions being extended towards said supporting portions and the wire coiled at the juncture therewith, means extending rearwardly from the toe engaging portions and insertible in a supported shoe or the like to maintain the same in normal shape, and means to engage the exterior of the heel of such supported shoe.

In witness whereof, I hereunto subscribe my name to this specification.

EUGENE L. CAVANNA.
